CLAIM

The ornamental design for a hair securing device, as shown and described.

DESCRIPTION

FIG. 1 is a top perspective view of a hair securing device showing the new design in an environment of use; FIG. 2 is a top perspective view of the hair securing device; and,

FIG. 3 is a top view of the hair securing device shown in FIG. 2.

The broken line showing of a head with hair in FIG. 1 depicts environment and forms no part of the claimed design.
